DESIGN FOR AN AUTOMOBILE

Jean Edouard Andreau, Daurat, near
Leognan, France

Application April 13, 1945, Serial No. 118,974
In France April 20, 1942

Term of patent 14 years

(Cl. D14—3)

To all whom it may concern:

Be it known that I, Jean Edouard Andreau, a citizen of the French Republic, residing at Daurat, near Léognan, department of Gironde, France, have invented a new, original, and ornamental Design for an Automobile, of which the following is a specification, reference being had to the accompanying drawings, forming part thereof.

In the drawings:

Fig. 1 is a three-quarter perspective view from the front showing my new design as it appears with the side door in open position;

Fig. 2 is a front perspective view;

Fig. 3 is a side perspective view;

Fig. 4 is a three-quarter perspective view from the rear; and

Fig. 5 is a top plan view.

The characteristic features of my design are shown by means of full lines in the drawings.

I claim:

The ornamental design for an automobile, substantially as shown and described.

JEAN EDOUARD ANDREAU.
